PISTON

Walter J. Six, Indianapolis, Ind.

Application March 2, 1935, Serial No. 8,997

8 Claims. (Cl. 309—14)

This invention relates to a piston having a compressible skirt with inherent spring tension adapted to operate within and conform to the wall of a cylinder, such as the cylinder of an internal combustion engine.

It has heretofore been the practice to so form the skirt of a piston that it will have some resiliency or give. Ordinarily this has been accomplished by providing it with a substantially longitudinal slot. The reason therefor is to compensate for variations in expansion under heat between the material of the piston, generally aluminum alloy, and that of the cylinder, generally cast iron. One difficulty with the usual type of split piston skirt is that it has little or no inherent spring tension resulting in its becoming set with such clearance relative to the cylinder as to result in piston slap, since this type of piston must be fitted with some clearance. Various methods have been devised for overcoming this difficulty by providing the skirt with an expander adapted to exert an outward pressure to maintain it in expanded cylinder contacting position. Other types of pistons are provided with a flexible steel skirt, but of a construction which is generally light and flimsy and not sufficiently firm and rigid as to properly perform the required functions of the piston skirt.

The object of this invention is to provide a piston not only with a flexible skirt, but one which will have inherent spring tension for normally maintaining it in a close fit with the cylinder wall under continued operative conditions. Furthermore, the skirt is of substantially normal character with the usual longitudinal split and is firm and rigid in respect to the piston head, although formed of a spring-like material, such as spring steel.

This may be accomplished by forming the skirt with an expansion formation along the edges of the split portion. In addition thereto there may be employed a spring web with a resilient formation tending to maintain the skirt in its expanded position but permitting it to conform with the cylinder wall. Such a skirt may be cast integral with the head, otherwise permanently secured thereto, or removably attached.

As a result of this arrangement, the piston may be fitted to a cylinder with the skirt in sliding contact, requiring no clearance. After substantial use, any wear will be taken up by the inherent spring tension, whereby replacement, re-boring, or the use of auxiliary expanders would not be required. While maintaining the

skirt in contact with the cylinder, the tension would be sufficiently light as not to cause resistance and heat generation by excessive frictional contact.

The full nature of the invention will be understood from the accompanying drawing and the following description and claims:

Fig. 1 is a plan view looking at the bottom of the piston mounted in a cylinder in compressed operative position. Fig. 2 is a section taken on the line 2—2 of Fig. 1. Fig. 3 is a section taken on the line 3—3 of Fig. 1. Fig. 4 is the same view as Fig. 1, showing a modified form of piston. Fig. 5 is a section taken on the line 5—5 of Fig. 4. Fig. 6 is the same view as Figs. 1 and 4, showing a second modification of the piston. Fig. 7 is a fragmentary section taken on the line 7—7 of Fig. 6.

In the drawing, reference being made to Figs. 1, 2, and 3, there is illustrated a cylinder 10 in which the piston is mounted, said piston being provided with the usual cast head 11 of aluminum alloy or the like, provided with the ring grooves 12, centrally formed web 13 and downwardly extending wrist pin bosses 14 through which the wrist pin is adapted to extend. Fixedly secured to the flanges 15 of the bosses 14 there is provided a pair of spring metal struts 16, said struts being formed adjacent one free end thereof with an expansion formation 17 in the form of an inwardly-extending fold. Said struts may be cast integrally with the boss portions, riveted, welded or otherwise fixedly secured thereto.

The piston skirt 18 is formed of spring steel or a similar metal, preferably having inherent spring tension, and is to be distinguished from aluminum or other more or less yieldable but not "springy" metal. This skirt extends about the boss portions, and terminates adjacent the lower portion of the head 11, said skirt being of the usual length and conformation as that of the standard type of split skirt piston. The skirt is suspended and carried by the ends of the struts 16, said ends being secured by rivet, weldings or otherwise, as indicated at 19. Intermediate the expansion formation 17 of the struts, the skirt 18 is split longitudinally thereof, the adjacent edges formed along the split portion thereof being turned inwardly, as indicated at 20 to provide a round exposed edge at the split of the skirt, and if so desired, provide a further expansion formation which becomes effective under abnormal compression and contraction.

From the foregoing, it will be understood that when the skirt of the piston is in its operative

position within the cylinder, the gap between the formations 20 of the piston is closed, and the expansion formations 17 are somewhat contracted. The spring tension, resulting therefrom, is sufficiently light as to not exert too much friction against the cylinder wall in operation. With the variation in expansion and contraction between the skirt and the cylinder due to changes in temperature and difference in metal, the skirt may be further compressed or will expand as the case may be, to maintain contact with the cylinder and prevent piston slap. This is accomplished through the flexibility and spring tension exerted by the expansion formations 17 of the struts and the formations 20 adjacent the split.

Figs. 4 and 5 illustrate substantially the same arrangement as above described, but wherein the bosses 114 are removably connected with the head 111 through the medium of the sheet metal bracket 112 which extends upwardly and is removably secured to the under surface of the head by the bolts 113, locked in position by the wire 113a. The bosses are provided with a flange 115 to which the struts 116, as well as the supporting bracket 112, are riveted. As above described, the struts are provided with the formation 117 while the skirt 112 is provided with a substantially longitudinal slot 120. By this arrangement, the skirt structure, together with the struts and bosses, may be separately formed and adapted to any piston head, if such arrangement is desirable.

In the forms illustrated in Figs. 6 and 7, the struts are eliminated, the expansive action and compression being accommodated by the inwardly-turned edges 220 of the skirt 218. The skirt in this modification is riveted or otherwise secured directly to the arcuately formed flanges 215 of the bosses 214. The bosses are integrally formed with the head 211. Under compression the spring steel skirt may be contracted by the yielding action of the abutting expansion formations 220 of the turned-in slotted portion. Said inwardly turned portions 220 may be so designed and formed as to act as a spring formation to any desired degree of compressibility.

The invention claimed:

1. A piston including a rigid head and a spring metal skirt connected with said head, said skirt being provided with a substantially longitudinal slot, the adjacent edges of the skirt defining said slot being curved inwardly in abutting relation to provide an expansion formation for permitting contraction of the skirt through their yielding action and exerting an expansive force under spring tension.

2. A piston having a rigid head with dependent bosses supported therefrom, a spring metal skirt having a substantially longitudinal slot formed therein, the free edges of said slot extending inwardly in curved abutting formation, spring metal struts secured to said bosses and having their outwardly extending free ends secured to said skirt, and an expansion formation in the form

of an inwardly curved fold provided in each of said struts adjacent the split portion of the piston for normally exerting an outward pressure thereon while permitting contraction thereof.

3. A piston including a rigid head and a depending skirt connected with said head, said skirt being provided with a substantially longitudinal slot, the adjacent edges of the skirt defining said slot being curved inwardly in abutting relation and formed of spring metal to provide an expansion formation for permitting contraction of the skirt through their yielding action and exerting an expansive force under spring tension.

4. A piston having a rigid head with dependent bosses supported therefrom, a piston skirt having a substantially longitudinal slot formed therein, the free edges of said slot being formed of spring metal and extending inwardly in curved abutting formation, spring metal struts secured to said bosses and having their outwardly-extending free ends secured to said skirt, and an expansion formation provided in each of said struts for normally exerting an outward pressure upon said skirt while permitting contraction thereof.

5. A piston having a rigid head with dependent bosses supported therefrom, a skirt having a substantially longitudinal expansion formation of spring metal formed therein extending from the bottom to the top of the skirt intermediate the bosses, spring metal struts secured to said bosses and having their outwardly extending free ends secured to said skirt, and an expansion formation provided in each of said struts for normally exerting an outward pressure upon the skirt while permitting contraction thereof.

6. A piston including a rigid head and depending substantially cylindrical and flexible spring metal skirt, said skirt extending about the entire periphery of the piston throughout substantially its entire length but provided with a substantially longitudinal slot for permitting it to be compressed and expanded under spring tension, and a spring metal strut securing said skirt to the head, said strut being provided with a flexible spring formation for normally exerting an outward pressure upon said skirt for increasing its radius of curvature, while permitting compression thereof against the inherent spring tension of said spring formation.

7. A piston comprising a head having a split skirt connected thereto, and longitudinally compressible flexible struts extending across said skirt and connected thereto, the said skirt and struts being fabricated wholly of spring steel.

8. As an article of manufacture, a bi-metallic piston of the separate head and skirt type, the said skirt being carried by the head and formed wholly of spring metal and being split longitudinally, and struts extending across and connected to said skirt, the said struts being provided with means exerting a continuous outwardly directed thrust on said skirt.
